United States Patent Office

Des. 196,335
Patented Sept. 17, 1963

196,335

DISPENSING CAN OR SIMILAR ARTICLE

Martin J. Mann, La Habra, Calif., assignor to Purex Corporation, Ltd., Lakewood, Calif., a corporation of California

Original design application Apr. 6, 1962, Ser. No. 69,609.
Divided and this application Feb. 5, 1963, Ser. No.
73,456

Term of patent 14 years

(Cl. D58—17)

FIG. 1.

FIG. 2.

FIG. 3.

FIG. 1 is a front elevational view of a dispensing can embodying my new design;

FIG. 2 is a rear elevational view of FIG. 1; and
FIG. 3 is a top plan view of FIG. 1.

The present application is a division of my co-pending application Serial No. D. 69,609, filed April 6, 1962, for Dispensing Can or Similar Article.

I claim:

The ornamental design for a dispensing can or similar article, substantially as shown and described.
